Neal Goldman, New York, N. Y., assignor to The International Silver Co., Meriden, Conn., a corporation of Connecticut

Application November 12, 1952, Serial No. 22,243

Term of patent 14 years

(Cl. D44—29)

To all whom it may concern:

Be it known that I, Neal Goldman, a citizen of the United States of America, residing in the Borough of Manhattan, city of New York, county of New York, and State of New York, have invented a new, original, and ornamental Design for a Cutlery Holder or Similar Article, of which the following is a specification, reference being had to the accompanying drawing, forming part hereof.

lery holder or similar article, showing my new design; Figure 2 is a top plan view; Figure 3 is a front elevational view; and Figure 4 is an end elevational view.

I claim:

The ornamental design for a cutlery holder or similar article, as shown.

NEAL GOLDMAN.
